CLAIM

The ornamental design for a music box with remote for crib, as shown and described.

DESCRIPTION

The nature and intended use of the article being an ornamental design that plays Christian music in a crib.

FIG. 1 is a front elevational view of the music box with remote for crib of the present invention;

FIG. 2 is a rear elevational view of the music box with remote for crib of FIG. 1;

FIG. 3 is a left side elevational view of the music box with remote for crib of FIG. 1, the right view being a mirror image thereof;

FIG. 4 is a top plan view of the music box with remote for crib of FIG. 1; and,

FIG. 5 is a bottom plan view of the music box with remote for crib of FIG. 1.
